CHAIR CAPABLE OF BEING PILED UP IN A VERTICAL DIRECTION

Friedrich August Schädler, Arbon, Switzerland

Application March 26, 1936, Serial No. 70,985
In Switzerland March 27, 1935

17 Claims.

(Cl. 155—2)

The subject of the present invention is a chair which can be piled up with equal or similar chairs.

In the accompanying drawings

Fig. 1 shows by way of example a form of construction of the chair in front elevation, the seat being in section.

Fig. 2 shows a longitudinal section through the plane of symmetry.

Fig. 3 shows a plan of the chair and, 10
Fig. 4 shows a cross section of the foot.

Figs. 5, 6 and 7 show further forms of construction of the foot.

Fig. 8 shows a further form of construction of the chair in side elevation.

15 The chair can be piled up to an unlimited extent in the vertical direction. The condition for unlimited piling up and removal in the direction of piling is that the extensibility of the chair measured in the direction of piling must not be larger at any point than the pile division. 20 (Pitch.) The direction of piling is determined by two suitable points of two chairs succeeding one another in the pile, the pile division being the distance between these points.

25 The chair is constructed for example as follows: To the two parallel foot bars 1, there are connected the two legs 2. They are connected to the rear end of the foot bars. The legs are connected together at the top by the transverse member 7. The foot bars, legs and transverse member may be formed in one piece. To the transverse member are welded the two rearwardly inclined back supports 3, which carry the back 4. To the lower horizontal portion of the back 35 supports the seat 5 is secured by means of the strengthening angle irons 6 and the bolts 8. Parallel to the foot bars there extends the supporting rail 9. On this rests the foot bar of the chair next above in the pile, whereby the pile 40 division is definitely determined and the other parts of the chair cannot come into contact with one another. In order to prevent the top chair from slipping off laterally, the supporting rail is constructed of channel shape at the top (Fig. 4). 45 The rail may also be provided with transverse ribs or projections 14 which engage with recesses 15 in the foot bar next above and prevent the top chair from slipping forwardly or backwardly (Figs. 5 and 6).

50 The legs are inclined laterally outwards and their distance apart at the upper ends measured inside, is somewhat larger than the width of the seat. The degree of inclination is determined by the thickness of the legs and the pile division. 55 In Fig. 4, s indicates the pile division, d the thick-

ness of the leg measured at right angles to its axis, a the thickness of the leg measured in the direction of piling, and z the angle of inclination thereof. The thickness a decreases as the angle z increases ($a=d/\sin z$). If now $a=s$ then when the uppermost chair is removed from the pile the legs thereof would just pass the legs of the next lower chair. In order that the piling and removal can be effected without trouble, the pile division s is somewhat larger than a whereby 5 a certain amount of play is left as shown in Fig. 1.

With an increasing division s the space taken up by a predetermined number of piled chairs increases. By the increase of the angle z the spacing between the foot bars increases and thus also 15 the requirement of floor space. The thickness d of the legs should therefore be as small as possible. The inclination of the back supports is effected according to the same points of view. Supporting rails, transverse member and seat 20 are so provided that when withdrawing the uppermost chair the seating surface of the next lower chair cannot be damaged as the lowest point of the transverse member is always located above the seating surface of the lower chair. Further, 25 the supporting rail is extended forwardly to such an extent that when rolling or sliding the upper chair on the front grooved portion of the supporting rail of the lower chair the transverse member of the first chair cannot come into contact with the seating surface of the second chair. This rolling or sliding movement is shown 30 in Fig. 8. By these two precautions, damaging of the chairs, even in the case of very careless piling or removal, is rendered impossible. 35

In Figs. 5 to 8 are shown four different forms of construction of the foot and supporting rail. In Fig. 5 the leg, foot bar and supporting rail consist of the same U-shaped piece of steel. In the case of the leg and foot rail this is upright (maximum moment of inertia). At the front curve however it is turned through 90° so that the channel is turned upwardly as supporting rail. The foot bar is provided on the under side with an indentation 15, and the supporting rail is provided on the top with a projection 14 so that a longitudinal movement of the upper chair in the pile is prevented. The construction in Fig. 6 is similar, but in this case the supporting rail is a 40 separate member. In both cases the rear end of the supporting rail is secured to the leg, e. g. by welding. (See 10, Fig. 4.)

45 Fig. 8 shows a supporting rail of U-shaped pressed sheet metal strips. It is bent at both ends and secured to the foot bar. At the ends the 50 55

struts of the U-iron are cut out so that the flanges 11 fit over the foot bars. In addition to an efficient connection this has the advantage that during piling these flanges 11 bear against the flanges 12 of the supporting rail of the chair next below at the points 13 and secure the chair in the longitudinal direction, thus rendering projections or the like unnecessary.

The position of the legs may also be different to the arrangements shown. In Fig. 1 it will be seen that the entire plane, determined by the foot bar and leg, remains free. The legs could also be applied at the front or at the middle, the chair could be provided with four legs, without in any way affecting the capability of being piled. The foot bars 1 may be connected by a cross-rod or member 16^x located near the front of the chair, and the supporting rails 9 may be provided with notches 16^y to receive the cross-bar of the next chair above when the chairs are piled up, as indicated in Figs. 1, 2 and 3. A lifting of the chair in the direction of piling in the present case, that is to say vertically upwards, is no longer possible in the latter case, but it would be necessary to move the chair, at least to such an extent that the transverse member comes to lie in front of the edge of the seat, forwardly from the pile. When this transverse member is secured to the foot bar it may also serve for effecting a locking in the longitudinal direction. The inner flanges of the supporting rails are then provided with recesses with which engages the transverse member of the foot bar of the chair next above.

The supporting rail may also be hingedly connected to the front end of the foot bar as shown in Fig. 7 and then turned about the bolt 16 and raised. The rear bent portion then bears against the leg near the seat. As the leg comes to lie in the channel of the U-shaped supporting rail, lateral movement and slipping off is not possible. The resilient chair may in this case be rendered rigid by raising the supporting rails. The supporting rail may also be so arranged that it can be raised through an angle of about 90°. In the raised position its rear end then comes to lie against the lower edge of the seat and thus supports directly the front part of the seat.

The supporting rails are in both cases so dimensioned that the seat may be somewhat raised when the supporting rails are to be brought into their raised position. The counteracting spring force of the leg then holds the supporting rail in its raised position without further securing means. These modifications can be provided in a similar manner when the legs are secured to the front ends of the foot bars. It is then only necessary to imagine the lower frame to be turned simply through 180° about its vertical axis.

What I claim as my invention is:

1. A chair capable of being piled in a vertical stack and comprising resilient legs, a seat and a back, the back being inclined rearwardly and the legs being inclined laterally outwards, said legs each including a horizontal foot bar and a horizontal supporting rail, the latter being located above the foot bar and parallel thereto, on which supporting rails the next higher chair in the stack rests, in virtue of all of which the chair can be piled in a vertical stack with others so that the uppermost chair can be removed forwardly from the pile in a horizontal direction.

2. A chair capable of being piled in a vertical stack and including resilient legs, a seat the legs being inclined laterally outwards, said legs each including a horizontal foot bar and a horizontal

supporting rail, the latter being located above the foot bar and parallel thereto, on which supporting rails the next higher chair in the stack rests, in virtue of all of which the chair can be piled in a vertical stack with others so that the uppermost chair can be removed forwardly from the pile in a horizontal direction, the supporting rails of a chair being so located with respect to the foot bars that they alone will support the weight of the next chair above in the stack, and hold the remaining parts of the supported chair out of contact with the remaining parts of the supporting chair.

3. Chairs capable of being piled in a vertical stack and each including a seat, legs inclined laterally outwards and terminating in horizontally extending supporting bodies comprising two similarly constructed rails and foot bars located on opposite sides of the chair, said rails having channels therein, said channels being adapted to receive the foot bars of the chair located next above in the stack in such a manner as to prevent lateral movement of the last mentioned chair.

4. Chairs capable of being piled in a vertical stack and each including a seat, legs inclined laterally outwards and terminating in horizontally extending supporting bodies comprising two similarly constructed rails and foot bars located on opposite sides of the chair, projections on said supporting bodies, said foot bars being provided with recesses, said projections being adapted to engage with the recesses of the foot bars in the chair next above in the stack so as to prevent longitudinal movement of the last mentioned chair.

5. A chair capable of being piled in a vertical stack and comprising legs, a seat and a back, the back being inclined rearwardly and the legs being inclined laterally outwards, said chair including a horizontally extending supporting body consisting of two similarly constructed supporting and foot members one at each side of the chair, said members being of such height that when the chair is at the top of a stack of others of like construction it can be moved forwardly in a horizontal direction without the seat, legs and back coming in contact with the chairs beneath in the stack.

6. A chair capable of being piled in a vertical stack and comprising legs, a seat and a back, the back being inclined rearwardly and the legs being inclined laterally outwards, said chair including a horizontally extending supporting body consisting of two similarly constructed supporting and foot members one at each side of the chair, said members being of such height that when the chair is at the top of a stack of others of like construction it can be moved forwardly in a horizontal direction without the seat, legs and back coming in contact with the chairs beneath in the stack, said supporting members extending forwardly to such an extent that when moving the foot member of the uppermost chair in a stack over the front end of the supporting member of the next lower chair no other parts of the chairs come into contact with one another.

7. A chair capable of being piled in a vertical direction comprising legs, a seat and a back, the back being inclined rearwardly to such an extent and the legs inclined laterally outwards to such an extent that the chair can be piled up vertically with others whereby the uppermost chair can be removed upwardly and forwardly from the pile, foot bars and supporting rails secured to said legs, a transverse member between the for-

ward ends of said foot bars, said transverse member being located beneath the front edge of the seat.

8. A chair capable of being piled in a vertical direction comprising legs, a seat and a back, the back being inclined rearwardly to such an extent and the legs inclined laterally outwards to such an extent that the chair can be piled up vertically with others whereby the uppermost chair 10 can be removed forwardly and upwardly from the pile, foot bars and supporting rails secured to said legs, a transverse member between said foot bars, said transverse member being located underneath the seat but at such a level that when 15 piling a number of chairs one upon the other the transverse members are always located between two seats.

9. A chair capable of being piled in a vertical direction comprising legs, a seat and a back, the back being inclined rearwardly to such an extent and the legs inclined laterally outwards to such an extent that the chair can be piled up vertically with others whereby the uppermost chair can be removed upwardly and forwardly 25 from the pile, foot bars secured to said legs, a transverse member between the forward ends of said foot bars, supporting members secured to said foot bars, said supporting members having recesses adapted to accommodate the transverse 30 member of the chair next above when a number of chairs are piled one upon the other whereby longitudinal movement of the upper chair is prevented.

10. A chair capable of being piled in a vertical 35 stack with others of like construction, said chair comprising legs, a seat and a back, the back being inclined rearwardly and the legs being inclined laterally outwards, said chair including a horizontally extending supporting body consisting 40 of a supporting bar and a foot bar at each side of the chair, said foot bars being fixedly secured to their respective legs, and said supporting bars being hingedly connected to their respective foot bars and adapted to be engaged 45 with the respective legs as braces when desired.

11. A chair capable of being piled in a vertical stack with others of like construction, said chair comprising a seat, a rearwardly inclined back and laterally outwardly inclined legs, a horizontal foot 50 bar for each leg, and a supporting member carried by each foot bar at an elevation above the same, in virtue of all of which when the chairs are stacked the upper chairs will be supported

by their foot bars resting on the supporting members of the next chair beneath.

12. A chair capable of being piled in a vertical stack with others of like construction, said chair comprising a seat, a rearwardly inclined back and laterally outwardly inclined legs, a horizontal foot bar for each leg, and a supporting member carried by each foot bar at an elevation above the same, in virtue of all of which when the chairs are stacked the upper chairs will be 10 supported by their foot bars resting on the supporting members of the next chair beneath, said supporting members being grooved slidably to receive the foot bars of a chair above when the chairs are stacked, in virtue of which an upper 15 chair can be slid over the next lower chair in a generally horizontal direction in placing and removing the chair from the stack.

13. A chair adapted to be piled with others in a vertical pile comprising a pair of legs, said 20 legs being inclined laterally outwards, horizontally disposed foot bars connected to the lower ends of said legs, a transverse member connecting together said legs at their upper end, a back secured to said transverse member, said back 25 being inclined rearwardly, a seat secured to said back and supporting members secured to said foot bars and located above said foot bars, the arrangement being such that when a plurality of 30 chairs are piled one upon the other the foot bars of one chair are supported by the supporting members of the next lower chair.

14. A chair according to claim 13, wherein each of the supporting members is of channel 35 section, the channel being of sufficient width to receive the foot bar of the chair next above.

15. A chair according to claim 13, wherein the legs, foot bars and transverse piece are constructed as an integral unit.

16. A chair according to claim 13, including a 40 projection of the upper side of each supporting member, said foot bars each having a recess therein, the projections of the supporting members being adapted to engage with the recesses 45 in the foot bars of the chair next above.

17. A chair according to claim 13, wherein the supporting members are hinged at their forward ends to the front ends of the foot bars, said supporting members being of channel section and adapted to be raised into an inclined position so 50 as to engage with said legs and assist in supporting said seat.

FRIEDRICH AUGUST SCHÄDLER.
